(57) **CLAIM**

The ornamental design for a tire as shown and described.

DESCRIPTION

FIG. 1 is a perspective view of a tire tread showing my new design, it being understood that the pattern is repeated uniformly throughout the circumference of the tread.

FIG. 2 is a front elevation view thereof. The top, bottom, and rear elevation views thereof are identical.

FIG. 3 is a left side view thereof; the right side view is identical; and,

FIG. 4 is an enlarged fragmentary view from upper 4-4 to lower 4-4 as provided in FIG. 2.

The broken lines are disclaimed and form no part of the claimed design. The dash-dot-dash lines indicate a boundary of the claimed design and are not themselves part of the claimed design. The surface shading lines and stippling in the drawings depict the character or contour of the surfaces represented and are not themselves part of the claimed design.
